UNITED STATES PATENT OFFICE

161,987

HEARING AID

Edward M. Yarbrough and John T. Macken, Minneapolis, Minn., assignors to The Microtone Company, Inc., St. Paul, Minn., a corporation of Minnesota

Application December 7, 1949, Serial No. 6,463

Term of patent 14 years

(Cl. D26—14)

To all whom it may concern:

Be it known that we, Edward M. Yarbrough and John T. Macken, citizens of the United States, respectively, residing at 135 Arthur Ave. S. E., and 4815 Dupont Ave. South, Minneapolis, county of Hennepin, State of Minnesota, have invented a new, original, and ornamental Design for a Hearing Aid, of which the following is a specification, reference being had to the accompanying drawings, forming a part hereof.

Fig. 1 is a front elevational view of a hearing aid showing our new design;

Fig. 2 is a side elevational view thereof; and

Fig. 3 is a top plan view thereof.

The dominant features of our design reside in that portion shown in full lines of the drawing.

We claim:

The ornamental design for a hearing aid, substantially as shown and described.

EDWARD M. YARBROUGH.

JOHN T. MACKEN.
